UNITED STATES PATENT OFFICE.

ARTHUR H. SYMONS, OF CHICAGO, ILLINOIS.

SHORE.

Application filed June 12, 1924. Serial No. 719,498.

The present invention relates to shores.

The present invention will be described particularly with reference to the type of shore used in the construction of concrete buildings, though as the description proceeds, it will be apparent that the invention is of much broader application.

In the construction of concrete buildings, it is the practice to shore up the false flooring by means of a number of uprights. Said uprights should be adjusted so that their tops have a predetermined level. Various expedients have been used for leveling the tops of the shores, but many of said expedients lack the advantage of ready adjustability combined with the strength required to hold the concrete after said concrete has been poured, or said expedients require the use of parts of rather special construction.

An object of the present invention is to provide an improved shore of simple construction which permits the use of timbers such as are commonly part of the equipment of builders.

A further object is to provide a shore which combines the advantages of ready adjustment with the advantage that timbers, as commonly provided by builders, may be utilized.

A further object is to provide a shore which permits ready and accurate adjustment, which may be readily removed from place without danger, and which utilizes timbers commonly found in the equipment of builders.

A further object is to provide a shore which combines the advantage of utilizing timbers, as commonly provided by builders, with the advantage that a non-slip gripping effect is had whereby the tendency to sag under load is minimized.

Further objects will appear as the description proceeds.

Referring to the drawings—

Figure 1 is a side view illustrating one embodiment of the present invention;

Figure 2 is a front view of one side of the embodiment illustrated in Figure 1;

Figure 3 is a back view of the embodiment shown in Figures 1 and 2;

Figure 4 is a sectional view taken along the plane indicated by arrows 4—4 of Figure 2;

Figures 5 and 6 represent details of construction; and

Figure 7 is a fragmentary view of a modified structure preferred by certain users.

The numerals 10—10 indicate a pair of standards which may be held in spaced relation at the bottom parts thereof by means of the strap 11 which is indicated as having a substantially U-shaped conformation, said strap 11 being fastened to the standards 10—10 by means of bolts 12—12. The standards 10—10 are held in spaced relation at their upper portion by means of the casting 13, which may be fastened to the standards 10—10 by means of bolts 14—14. The casing 13 and the strap 11 will hold the standards 10—10 securely in substantially parallel relation whereby said standards 10—10 will form guides for the slide 15. The slide 15 will preferably be of rectangular cross-section and it will be found convenient in the practice of the present invention to use, for said slide 15, a timber having a cross-sectional dimension, on each side, of four inches, timbers of this dimension being common equipment of builders. The bracket 13 will be provided with a hole of sufficient dimension to permit free sliding movement of slide 15 therethrough. Said bracket 13 serves as a guide for the slide 15.

The upper portions of the standards 10—10 may be cut away on opposed faces and may be lined with members 16—16 which may be bolted to said standards 10—10. Mounted to have a free sliding movement between the linings 16—16 is the casting 17, which casting 17 has the portion 18 engaging one side of the slide 15 and the portion 19 adapted to provide a housing for certain wedging members for abutting relationship with the opposite side of said slide 15. The casting 17 is also provided with the walls 19'—19' which connect portions 18 and 19. Said walls 19'—19' embrace the slide 15, whereby casting 17 encircles slide 15.

The portion 18 is provided with the off-set member 20 which forms a seat for a nut 21, which nut has screw-threaded engagement with the bolt 22. Said bolt 22 is supported by the off-set portion 23 of the bracket 13. The off-set member 20 of the casting 17 will preferably be so formed as to provide a pocket for the nut 21 to prevent rotation of said nut 21. The head of the bolt 22 above the off-set portion 23 of the casting 13 will be so placed, however, that a

wrench may readily be applied thereto for the purpose of communicating turning movement to said bolt 22. The portion 18 of the casting 17 will be provided with a pair of laterally extending lugs 24—24 adapted to engage the adjacent side edges of the linings 16—16. The remainder of the portion 18, however, will preferably lie within the boundaries of the opposed faces of linings 16—16.

Referring now to the housing 19 on the opposite side of the shore, said housing is provided with a pair of lugs 25—25 adapted to engage the adjacent edges of the linings 16—16. Mounted within the housing 19 is the metallic gripping member 26 having the offset lugs 27—27 for engaging with the upper side of housing 19. One side of the gripping member 26 is provided with the horizontally extending ribs 28—28, which ribs 28—28 are adapted to dig into the adjacent face of the slide 15, and for this reason, the horizontal dimension of the gripping member 26 should, with the exception of the lugs 27—27, be of less width than the space between the linings 16—16, or at least the ribs 28—28 should be within the space between linings 16—16 whereby said linings will not interfere with the gripping action of member 26. The outer side of the gripping member 26 is provided with the outstanding stud 29 adapted to receive the wedge member 30. Said wedge member 30 is provided with the slot 31 within which the stud 29 is adapted to ride, and is also provided with the tapering portions 32—32 adapted to engage with an inner wall of the housing 19. The wall of housing 19, adapted to engage the tapering portions 32—32 of the wedge member 30, will preferably be tapered to conform to said tapering members 32—32. Preferably, the stud 29 will be provided with an enlarged portion 33 at its outer extremity whereby to prevent loss of the gripping member 26 and wedge member 30 when the slide 15 is removed from between the standards 10—10.

The upper end of the wedge member 30 and the lower end thereof will preferably be provided with portions adapted to receive hammer blows, whereby said wedge member may be driven into wedging relation with its adjoining parts or moved from wedging relation therewith.

Certain contractors prefer to use shores having a rigid abutting relationship between the slide and its supporting member. The present invention is particularly useful in this way. Figure 7 illustrates a slide 15 having secured thereto, on its front side, an elongated metal plate 35 having recesses 36—36 for receiving the ribs 28—28 of the gripping member 26. The metal plate 35 may be applied or removed without the exercise of any great amount of skill and has

the advantage that the ribs 28—28 of the metallic gripping member 26 have a positive abutting relationship with the metallic plate 35 in the recesses thereof. It will be understood, of course, that instead of having ribs on the plate 35 and corresponding recesses on the plate 35, the plate may be provided with the ribs and the gripping member 26 provided with the corresponding recesses.

The mode of operation of the present invention will be clear without detailed description. It may be stated briefly, however, that with the wedge member 30 loosened from wedging relation with its cooperating parts the slide 15 may be raised relative to the standards 10—10 to approximately the position required for the top of said slide 15. The top portion of the wedge member 30 may then be struck a blow in a downward direction whereby said wedge member 30 will force the gripping member 26, including the ribs 28 thereof, into firm gripping relationship with the slide 15; or in case the plate 35 is being used the wedge member 30 will hold the ribs 28 of gripping member 26 in firm gripping engagement with the recesses 36—36 in said plate 35. Turning movement will then be applied to the bolt 22 to communicate a lifting movement to the slide 15 to bring the top thereof positively and accurately to the desired level.

Particular note should be made of the fact that the full gripping effect between the gripping member 26 and the slide 15 is accomplished before the load is applied to slide 15, the advantage being obtained that there is a minimum tendency of the slide 15 to slip from its adjusted position under load.

When it is desired to release the shore from its holding position, it is only necessary to give the lower portion of the wedge member 30 a blow in an upward direction to release the wedging relationship between the wedge member 30 and its cooperating parts. A relatively light blow will allow the slide 15 to fall a few inches. The wedge member 30 will, under the influence of gravity, fall to wedging relationship with the slide 15 before the slide 15 will have had a chance to travel far. The danger is obviated, therefore, that the slide 15 will drop with a sudden jar from its upper position to a position at the base of the standards 10—10.

The present invention combines the advantages above referred to with the advantage that the slide 15 may be embodied in any ordinary timber such as is commonly found in the equipment of building constructors. It will be noted that the wedging action between the gripping member 26 and portion 18 is substantially transversely of the slide 15, whereby tendency of slide 15

to get out of proper alignment is minimized.

Though a preferred embodiment of the present invention has been described in detail, many modifications will occur to those skilled in the art. It is intended to cover all such modifications that fall within the scope of the invention as defined by the appended claims.

I claim:

1. A shore comprising a pair of standards, means for holding same in substantially parallel relation, linings upon opposed faces of said standards, a slide mounted between said standards, means mounted at the upper extremities of said standards for guiding said slide, means encircling said slide and having abutting relation with said linings, said encircling means being provided with gripping means for holding said slide and adjustable means for governing the position of said encircling means relative to said standards.

2. A shore comprising a pair of standards, means for holding same in substantially parallel relation, linings upon opposed faces of said standards, a slide mounted between said standards, means mounted at the upper extremities of said standards for guiding said slide, means encircling said slide and having abutting relation with said linings, said encircling means being provided with gripping means for holding said slide and adjustable means for governing the position of said encircling means relative to said standards, and wedging means mounted within said encircling means for controlling the operation of said gripping means.

3. A shore comprising a pair of standards, a slide mounted between said standards, said shore being provided with means at the upper extremities of said standards for guiding said slide, and a holding member encircling said slide, said holding member including a gripping member and a wedge for operating same, said holding member being

disposed to exert a holding force substantially transversely of said slide.

4. A shore comprising a pair of standards, a slide mounted between said standards, said shore being provided with means at the upper extremities of said standards for guiding said slide, a holding member encircling said slide, said holding member including a gripping member and a wedge for operating same, said holding member being disposed to exert a holding force substantially transversely of said slide, and adjustable means for governing the position of said holding member relative to said standards.

5. A shore comprising a pair of standards, a slide mounted between said standards, said shore being provided with means at the upper extremities of said standards for guiding said slide, and a holding member encircling said slide, said holding member including a gripping member and a gravity responsive wedge for operating same, said holding member being disposed to exert a holding force substantially transversely of said slide.

6. A shore comprising a pair of standards, means for holding same in substantially parallel relation, linings upon opposed faces of said standards, a slide mounted between said standards, means mounted at the upper extremities of said standards for guiding said slide, means encircling said slide and having abutting relation with said linings, said encircling means being provided with gripping means for holding said slide and screw-threaded means for adjusting the position of said encircling means relative to said standards and gravity responsive wedging means mounted within said encircling means for controlling the operation of said gripping means.

Signed at Chicago, Illinois, this 10th day of June, 1924.

ARTHUR H. SYMONS.
